UNITED STATES PATENT OFFICE.

EDMUND R. ANGELL, OF DERRY, NEW HAMPSHIRE.

ACETYLENE-GENERATOR.

1,111,726.

Specification of Letters Patent. Patented Sept. 29, 1914.

Application filed August 5, 1907. Serial No. 387,215.

To all whom it may concern:

Be it known that I, EDMUND R. ANGELL, a citizen of the United States, residing at Derry, in the county of Rockingham and 5 State of New Hampshire, have invented a new and Improved Acetylene-Generator, of which the following is a specification.

It belongs to that class of acetylene generators known as carbid-feed, in which calcium carbid, in small quantities at a time, is 10 automatically dropped into water.

The object of my invention is to produce a carbid-feed acetylene generator, which either admits no air, or the least possible amount of 15 it during recharging.

The means for holding the two parts together are completely described and claimed in another application Serial No. 616025 filed Mar. 21, 1911. This application treats 20 the generating chamber as rigidly attached to the body of the machine.

The figure is a sectional elevation of the device.

A and B, represent two concentrically located hollow cylinders, and C, the gas holder floating in liquid in the annular space between them.

The annular disk D fastens the two cylinders together and forms the bottom of the 30 gas holder seal.

E is the carbid chamber, or hopper. It is formed partly by the upper part of the cylindrical wall B, and has a frusto-conical bottom with its larger end fastened to said 35 wall roundabout and its smaller end downward and open for the mouth.

F is a conical stopper adapted to be drawn up into the mouth of the hopper to close it against the passage of carbid, but fitting 40 loosely enough for gas to pass easily either way. It is attached, at its vertex, by a ball and socket joint to the lower end of the rod G. This rod is suspended, at its upper end, from the central part of the transverse lever 45 H by the pivot I. The lever H is fulcrumed at J to the support K, which, in turn, is fastened to the side of the carbid chamber and extends inwardly to the center.

S is a guard sleeve, rigidly fastened to the 50 support K.

T is a perforated disk lying upon the top

of the guard sleeve. The rod G passes through both the disk and sleeve. They keep the carbid from touching the rod and impeding its motion too much. The disk is 55 free to move laterally on the top of the sleeve, taking the swaying motion of the rod sliding through it. The weight L is pivotally suspended from the short arm of the lever H at M. This weight hangs down in 60 the upper part of the upright pipe N, which is fastened tightly in the outer edge of the bottom of the hopper, and extends downwardly just below the gasholder seal where it connects with the service pipe O. Thus 65 the pipe N serves both as a guide for the weight L and part of the gas channel. Carbid is prevented from falling from the hopper into this pipe by the sides of the support K and its cover R. The gas, after generation, passes from the generating chamber up through the space between the loosely fitting stopper and the hopper's mouth. Thence through the interstices between the 70 particles of carbid, where it is dried. It then 75 passes down through the pipe N into the service pipe O.

I' is a drip-guard to prevent condensation of moisture from running down the side of the hopper to wet and impede the feed.

U is a friction wheel on the long arm of the lever H adapted to roll on the lower surface of the disk V, which is attached transversely to the end of the screw W. This screw has a coarse thread to hasten its travel. 85 It works in the nut X, which is secured in the top of the gasholder, so that when the screw is turned down completely most of it is within the gasholder; and when the screw is turned up to its full extent most of it is 90 without the gasholder.

Y is the knob for turning the screw and Z is packing between it and the nut to secure a tight joint.

A' is a nipple fixed in the top of the gas- 95 holder through which carbid is introduced into the hopper. B' is the cap which closes it, and C' is a packing ring between the cap and nipple.

D', D' are guide rods for the gasholder. 100 They are supported by attachments on the hoop F' at the top of the gasholder seal; and

E' E' are guide arms on the gasholder engaging the rods.

G' is a rack on the gasholder.

H' is a thumb screw threaded through the 5 hoop F' and the wall of the tank A to engage the rack. The service of the screw and rack is to put the machine out of operation by suspending the gasholder, should it ever be desirable; and thereby enable the operator 10 at any time to learn whether the hopper contains much or little carbid, or to introduce more before all is exhausted.

A'' is the generating chamber formed by the extension downward of the cylinder A 15 and is provided with a suitable bottom.

B'' is a drain pipe provided with a valve. It is fastened through the wall of the generating chamber at a suitable height, and its inner end is bent downwardly terminating 20 near the bottom of the chamber so that the part of the drain pipe thus made upright, is longer than the water column within it, which is sustained by the gas pressure when said valve is open. This construction provides a trap, so that, during the removal of 25 residuum, neither gas can escape from the machine nor air enter it.

C'' is a water supply pipe, entering the generating chamber through the opening 30 D''. The top of D'' is not farther from the bottom of the chamber than is the inner end of the drain pipe B''. This construction also provides a trap to prevent the escape of gas or ingress of air.

E'' is a rod within the pipe C'', bent outwardly at the top to form a handle, and inwardly at the bottom to carry the agitator blade F''. It turns in the supports G'' G'', which are attached to the wall of the chamber.

The machine is put into operation as follows: It is placed upon a level foundation and connected with the piping of the building. A vent-cock in the service pipe is 45 opened to allow escape of air. The gasholder seal is filled with liquid. The generating chamber is filled with water poured through the water-supply pipe C''. The screw W is turned up to close the feed. It 50 is to be noted that when the gasholder and disk V, are in their lowest position, the long arm of the lever H is fully depressed and the mouth of the hopper wide open. But when the disk V is in its highest position, 55 the long arm of the lever H is fully elevated, although the gasholder is in its lowest place, and the stopper F closes the mouth of the hopper. With the hopper closed, carbid is introduced into it, and the cock in the service pipe is closed. The screw W is then 60 turned down. As the disk V engages the friction wheel U to depress the long arm of the lever H, the stopper F, is partly removed from the mouth of the hopper, carbid

falls into the water of the generating chamber A'', and gas is generated, causing the gasholder to rise, so that the disk V, although in its lowest position relatively to the top of the gasholder, is above contact with the lever H, and the conical stopper, 70 forced into the mouth of the hopper by the action of the weight L, prevents the fall of more carbid. The burner cocks along the line of piping are now opened. As the mixture of air and gas escapes, the gasholder 75 settles, again bringing the disk V against the wheel U to depress the lever. This continues till enough carbid falls into the water for the resulting gas to raise the gasholder and stop the feed. This process repeats. 80 As soon as the air is removed from the machine and system of piping so that the gas burns brightly, the cocks are closed.

The method of recharging does not require the machine or the piping to be vented. 85 Practically, no air enters the machine during recharging and no gas escapes, except what the carbid displaces when it is poured into the hopper. The effect of air mixed with the gas, is to dim the lights. My invention prevents this very annoying and wasteful trouble, which is usually incident to recharging. No air has to be admitted to allow the residuum to flow out, since gas is generated to take the place of it. Herein is 90 a distinguishing merit of my invention.

When recharging is necessary, the gasholder is completely down. Recharging with carbid is first in order. The screw W is turned up to allow the feed to close and the 100 carbid is introduced in the manner described. Then the screw W is turned down so that the evolution of gas will raise the gasholder. Then the sediment in the generating chamber is stirred up by means of the 105 agitator. The draw-off B'' is opened. As the residuum flows out, the gasholder descending, forces gas through the space around the loosely fitting stopper F into the generating chamber A'', the disk on 110 the end of the screw W engages the wheel U to depress the long arm of the lever H, the feed opens, carbid drops, and gas is generated to occupy the place of the receding residuum, so that it can continue to flow out. After all the residuum has run out, which 115 the trap formed by the drain pipe will permit, the draw-off valve is closed. The generating chamber is refilled with water in the manner described. The introduction of 120 water displaces the gas, which causes the gasholder to rise to make room for it.

Having thus described my invention, I claim as new and desire to secure by Letters Patent:

1. In an acetylene generator, a floating gasholder and generating chamber, in combination with mechanism for feeding carbid

into water, consisting of a carbid hopper with a frusto-conical bottom, the small end being downward and open for the mouth; a conical stopper adapted to be drawn into 5 said mouth to close the feed; a transverse lever within the upper portion of the hopper, extending diametrically across it with its fulcrum upon a support projecting inwardly from its attachment to the side of 10 said hopper; a rod attached at its lower end to the vertex of the conical stopper, pivotally suspended at its upper end from the middle part of said lever, and working vertically in the axial line of the hopper; a 15 guard sleeve and disk-like cover therefor, through which said rod works, protected thereby from interfering contact with carbid, the guard sleeve being firmly fastened to the fulcrum-support of the lever, and the 20 disk-like cover free to move laterally on the top of said sleeve with the swaying of the rod; a weight pivotally suspended from the short arm of the lever and working vertically in an upright pipe, which is tightly 25 fixed in the outer edge of the bottom of the hopper and forms part of the gas channel; and a friction wheel on the end of the long arm of the lever adjusted to receive motion from the gasholder when nearly down to 30 actuate the feed.

2. In an acetylene generator, a floating gasholder and generating chamber in combination with mechanism for feeding carbid into water consisting of a carbid chamber, 35 or hopper, with a frusto-conical bottom, the small end being downward and open for the mouth; a conical stopper adapted to be drawn into said mouth to close the feed; a transverse lever within the upper portion of 40 the hopper, extending diametrically across it with its fulcrum upon a support projecting inwardly from its attachment to the side of said chamber; a rod attached at its lower end to the vertex of the conical stopper, 45 pivotally suspended at its upper end from the middle part of said lever, and working vertically in the axial line of the hopper; a guard sleeve with a disk-like cover therefor, to prevent the carbid interfering with the 50 motion of said rod which works through them, the guard sleeve being fastened to the fulcrum-support of the lever and the disk-like cover being free to move on the top of said sleeve with the swaying of the rod; a weight pivotally suspended from the short 55 arm of the lever and working vertically in an upright pipe, which is fixed in the outer edge of the bottom of the hopper and forms part of the gas channel; a friction wheel 60 on the end of the long arm of the lever adapted to receive motion from the gasholder when nearly down to actuate the feed; a screw working vertically through a nut secured in the top of the gasholder, a

convenient knob being provided for turning 65 the screw with packing between it and said nut; a disk fixed transversely on the end of said screw and adapted to engage said friction wheel to depress the long arm of said lever when said screw is turned down, and 70 to be raised from contact therewith when the screw is turned up, said mechanism constituting means for putting the gas- 75 holder in and out of control of said feeding device.

3. In an acetylene generator, a floating gasholder and generating chamber in combination with mechanism for feeding carbid into water, consisting of a carbid chamber, or hopper, with a frusto-conical bottom, the 80 small end being downward and open for the mouth; a conical stopper adapted to be drawn into said mouth to close the feed; a transverse lever within the upper portion of the chamber, extending diametrically across 85 it with its fulcrum upon a support projecting inwardly from its attachment to the side of said chamber; a rod pivotally suspended at its upper end from the middle part of 90 said lever, and working vertically in the axial line of the hopper; a ball and socket joint at the lower end of said rod connecting it to the vertex of the conical stopper whereby said stopper seeks the place of least 95 resistance to close the feed; a weight pivotally suspended from the short arm of the lever and working vertically in an upright pipe which is fixed in the outer edge of the bottom of the hopper and forms part of the gas 100 channel; and a friction wheel on the end of the long arm of the lever adapted to receive motion from the gasholder when nearly down to actuate the feed.

4. In an acetylene generator, a gasholder; a generating chamber; an annular gasholder 105 seal; mechanism for feeding carbid into water consisting of a carbid chamber formed by the upper part of the inner wall of said annular seal and a frusto-conical bottom, the small end thereof being the mouth of the 110 chamber; a lever within the top of the chamber and extending diametrically across it and fulcrumed to a rigid support projecting from the side of the chamber; a rod pivotally suspended from the middle part of 115 said lever; a conical stopper adapted to close the mouth of said chamber; a ball and socket joint which attaches said stopper to said rod; a guard sleeve fastened to said rigid support and through which said rod works 120 vertically; a perforated disk lying upon the top of said sleeve through which said rod also works, and which moves laterally on the top of said sleeve with the swaying motion of the rod; a weight suspended from the 125 short arm of said lever; and a friction wheel on the end of its long arm; in combination with means for putting said feeding mecha-

4
nism in and out of control of the gasholder, consisting of a nut rigidly fixed in the top thereof, a screw working vertically through said nut and top of gasholder; a disk trans-

5 versely fixed on the end of the screw within the gasholder and adapted to engage said friction wheel, whereby the lever may be de-

pressed to open the feed, or allowed to rise by the influence of said weight to close it at will.

EDMUND R. ANGELL.
